UNITED STATES PATENT OFFICE.

ALFRED E. ROBERTS, OF SAN FRANCISCO, CALIFORNIA, ASSIGNOR OF ONE-FIFTH TO
HARRIET M. ROBERTS, OF SAN FRANCISCO, CALIFORNIA.

WASHING MACHINE.

Application filed December 22, 1920. Serial No. 432,397.

To all whom it may concern:

Be it known that I, ALFRED E. ROBERTS, a citizen of the United States, residing at San Francisco, in the county of San Francisco, State of California, have invented a new and useful Washing Machine, of which the following is a specification in such full and clear terms as will enable those skilled in the art to construct and use the same.

10 This invention relates to a washing machine and its object is to produce an apparatus which will be capable of being applied to any ordinary stationary wash trays.

It will be understood by those skilled in 15 the art that the ordinary electric washing machines are cumbersome and occupy much needed space, whereas most modern houses are equipped with a pair of stationary wash trays over which this apparatus can be installed without occupying any additional 20 floor space and which have the usual water and waste connections.

Another object of the invention is to provide a washing machine of the so-called 25 vacuum type which will be provided with means for balancing the reciprocating parts thereby reducing the amount of power necessary to operate the apparatus.

A further object of the invention is to produce 30 an apparatus which will have its electric motor installed in a location where it is not likely to be wet by the splashing of water from the washing machine.

Another object of the invention is to produce 35 a frame for carrying the apparatus which will be compact and easily assembled and which can be easily applied to the house where the machine is to be installed by simply nailing a pair of cleats to the house or 40 room wall.

Another object of the invention is to provide means whereby the position that the 45 vacuum cups occupy may be adjusted to accommodate the machine to larger or smaller masses of clothing in the wash tub.

Another object of the invention is to provide means whereby the vacuum cups may be oscillated from one position to another position when the apparatus is raised out of engagement with the clothes so as to cover

substantially the entire area of the bottom of the wash tray.

Another object of the invention is to produce a driving gear which will be capable of driving a spur gear and a worm gear from 55 the same teeth, the face of the spur gear teeth being cut to mesh with both of said gears, thereby enabling the vacuum cups to be oscillated horizontally with only one extra gear. 60

Other objects of the invention will appear as the description proceeds.

An embodiment of the invention is shown in the accompanying drawings in which the same reference numeral is applied to the 65 same portion throughout, but I am aware that there may be modifications thereof.

Figure 1 is a front elevation of the complete machine, the wash tubs and a portion of the enclosing casing being shown in section. 70

Fig. 2 is a side elevation of the complete machine with the wash trays and a portion of the enclosing casing being cut away for purposes of illustration. 75

Fig. 3 is a plan view of the operating mechanism on the line 3—3 Fig. 1.

Fig. 4 is a plan view of the arrangement for shifting the vacuum cup from one position to the other. 80

Fig. 5 is a vertical sectional view of a portion of the vacuum cup shifting apparatus.

Fig. 6 is a view in elevation of the combined spur and worm gear used for transmitting the power to the vacuum cups and 85 to the apparatus for shifting the vacuum cups.

Fig. 7 is a plan view of a wash tray illustrating the two positions the vacuum cups operate in. 90

Fig. 8 is a view of the operating mechanism looking from the back with the back of the enclosing casing and the cleats removed.

Fig. 9 is a view of the operating mechanism looking from the left of Fig. 1, the outside of the casing being removed for purpose of illustration. 95

The numeral 1 indicates an ordinary form of double wash tray, one side of which has the cover 2 and the other side of which has 100

the cover 3. The cover 3 is supported by four members 4 to 7 inclusive which are connected together to form an extension of the edges of the wash tray, so as to give additional space for the operation of the vacuum cups. These four members are held in place on the upper edge of wash tray to which they are applied by means of a plurality of depending lugs 8 to 13 inclusive.

10 The driving apparatus is installed in a framework having the sides 14 and 15, back members 16 and 17, cleats 18 and 19 and top 20. This frame-work is ordinarily made of wood and has the cleats 21 to 24 inclusive to 15 stiffen it. The top 20 is extended beyond the side 15 far enough to form a support for the motor 26 to the under side of which the motor is bolted.

10 The lower cleat 19 carries a bracket casting 27 which has a bearing in its underside for a horizontal shaft 28, said shaft also extending into a bearing 29 carried by a bracket 30 bolted to the outside of the side 15. This shaft also supports the gear 31, but 25 which gear is revoluble thereon. The shaft 28 also carries rigidly connected therewith a pinion 32, grooved pulley 33 and bevel gear 34. The upper portion of the bracket 27 is provided with a bearing 35' for a shaft 35, 30 said shaft carrying a combined spur and worm gear 36 and a small pinion 37. The gear arrangement is such that the gear 32 drives the combined worm and spur gear 36 in about a one to four relation while the pinion 37 drives the gear 31 in a one to four relation thereby reducing the speed of the gear 31 to one-sixteenth that of the rate of rotation of the shaft 28.

40 A belt 38 connects the motor pulley 39 with the pulley 33. The bracket 27 has a vertical bearing 41 for the shaft 42 which latter has the spiral gear 43 on its upper end in mesh with the spiral cut teeth of the gear 36.

45 It will be understood that the spur gear 36 is traveling at a comparatively high rate of speed with respect to the gear 31 so that if its teeth are of the same width as the gear 31 they will be strong enough to admit of the necessary spiral coating to permit that gear to also engage and drive the spiral gear 43.

50 The gear 31 is connected to a link 44 and said link is in turn connected at its opposite end to a movable bracket 45 on the vertical shaft 40. The bracket 45 is held in place by means of two fixed collars 46 and 47 and it has an arm extending forwardly as indicated at 48 to which a short length of cable 49 is connected, said cable 49 passing over a 55 grooved pulley 50 carried by two depending brackets 51 connected to the under side of the top 20. The other end of the cable 49 is connected to a long heavy spiral spring 52. The lower end of the spiral spring is 60 connected to a lug 53 into which a bolt 54 is 65 connected and the bolt 54 extends through a forwardly projecting lug 55 on the bracket 27. The object of this construction is to increase or diminish the tension of the spring as may be desired.

70 The shaft 40 is vertically slidable in a bearing 65 bolted to the bracket 27 and in a bearing 56 bolted to the under side of the casing top 20.

75 In order to prevent the link 44 from causing the shaft 40 to bind as it passes through the bearing 65 and the bearing 56, bolted to the under side of the top 20 the bracket 45 is extended far enough to receive the lower end of a short shaft 57 passing through another 80 bearing 58 forming a part of the bracket in which the bearing 56 is formed.

75 The shaft 40 is slotted as indicated at 59 and a flat key 60 extends through said slot for oscillating the shaft 40. The key 60 has 85 two lugs 61 and 62 thereon through which a pin 63 extends.

80 Bolted to the bracket 27 is a plate 64 which carries the bearing 65 surrounding the shaft 40 and said bearing is provided 90 with an opening on both sides thereof to permit the key 60 to oscillate the shaft 40 without turning it completely around.

85 A link 66 is connected to a pin 67 on the spiral gear 43 and at its opposite end the 95 link has a slot 68 through which the pin 63 extends. The pin 63 and the key 60 are retained in place by cotter pins placed through suitable openings therein.

90 The timing of the spiral gear and the 100 other gears is such that during the period of each upward movement of the shaft 40 the link 66 will shift said shaft and its supported vacuum cups from one position to another position in the wash tray, thereby 105 covering practically the entire area of the wash tray. Since it would be inconvenient to ship very long apparatus, the shaft 40 is no longer than the enclosing casing and it is provided with a coupling 69 which is in 110 turn connected to a shaft 70 connected to the tubular member 71 which carries the vacuum cups.

95 The vacuum cups are as flat as is consistent with the work required of them and are 115 indicated at 72 and 73. They have upwardly projecting lugs 74, to 77 inclusive through which lugs, the horizontal tubes or shafts 78, 79 extend and said vacuum cups may oscillate about the axis of said horizontal shafts to accommodate themselves to uneven piles of clothes in the tub.

100 The shafts 78, 79 are suitably connected to a fitting 80 on the lower end of the tube 71.

105 In order to provide for the driving of a 125 wringer by the same apparatus, the bevel gear 34 is arranged to be in mesh with a bevel gear 81 on the upper end of a vertical shaft 82, said shaft extending to the wringer and operating it. In order to provide for 130

swinging the wringer around, the side 7 has a support 83 provided with an upwardly extending pin 84 which may be secured to the side 7 by means of the wing nut 85.

5 The operation of the apparatus is as follows:

Assuming the tub to be filled with water to a suitable depth and having the proper amount of clothing placed therein, the motor 10 is started. As it operates the pulley 33, the vacuum cups will be raised and lowered at a rate of one-sixteenth or less if desired the rate of rotation of the pulley 33. During each upward movement of the vacuum cups the 15 spiral gear 43 operated by gear 36 will shift the shaft 40 carrying the vacuum cups from the position it then occupies to a different position thereby fully covering the clothing in the tub. Since the spring 52 is made stiff 20 enough to just support the vacuum cups and shafting connected therewith, the only work the motor is called upon to do is that due to the punching of the clothes and not that due to raising and lowering the vacuum cups 25 and their attached load.

It will also be noted that if the tub is filled unusually full of clothes, that it is possible to adjust the position of the vacuum cups by raising or lowering the tube 71 30 with respect to the shaft 70, a suitable pin 83 being used to connect the two parts together. It will of course be apparent that other forms of vacuum cups may be used on the lower end of the tube 71, if it is not desired to use the form shown herein.

In order to close the frame it has a metal bottom plate 90 and a frame 91 on the front which is provided with a window 92.

What I claim is as follows, but various 40 modifications may be made in the construction shown in the drawings and above particularly described form, within the purview of my invention:

1. A machine of the class described comprising the combination with a wash tray 45 of a frame adapted to be secured to a fixed structure above the wash tray, a vertically extending shaft passing through said frame, vacuum pans supported by said shaft for kneading the clothes in the wash tray, operating mechanism carried by the frame adapted to vertically reciprocate and horizontally oscillate the vacuum pans, and a long spiral spring for substantially balancing the weight of the supporting shaft and 50 vacuum pans.

2. An apparatus of the class described 55 comprising a wash tray, a frame adapted to be connected to a fixed support above the wash tray, a vertically extending shaft passing through the frame, driving mechanism carried by said frame adapted to vertically reciprocate and horizontally oscillate said shaft, and a pair of vacuum pans at the 60 lower end of the shaft pivotally mounted to

oscillate about a substantially horizontal axis, for kneading the clothing in the wash tray.

3. An apparatus of the class described comprising the combination with a wash tray of a frame adapted to be secured to a fixed support above the wash tray, a vertically extending shaft passing through the frame, driving mechanism carried by said frame adapted to vertically reciprocate and horizontally oscillate said shaft, vacuum pans at the lower end of the shaft oppositely positioned and adapted to have a pivotal movement about an axis at right angles to the supporting shaft, driving mechanism for operating the shaft and vacuum pans, and means to partially support the weight of the reciprocatory shaft and vacuum pans to reduce the power required to operate the apparatus. 85

4. An apparatus of the class described comprising a wash tray, a frame adapted to be secured to a fixed support above the wash tray, a vertically extending shaft passing through said frame, means carried by the frame to vertically reciprocate and horizontally oscillate said shaft, a transversely extending bar at the lower end of the shaft, vacuum pans pivotally mounted on said transverse bar for kneading the clothes in the tray, and a combined spiral and spur gear for converting the rotary motion of a motor shaft into a reciprocatory and oscillating motion of said vertically extending shaft. 90

5. An apparatus of the class described comprising a frame, a driving mechanism carried thereby, a vertically reciprocatory clothes washing mechanism supported in the frame, a long spiral spring to balance 105 the weight of the clothes washing mechanism, a movable arm on the clothes washing mechanism to which said spring is connected, means connected with the driving mechanism and said arm to reciprocate the clothes washing mechanism vertically and a spiral gear on a vertical axis to oscillate the clothes washing mechanism from one position to another position upon each upward movement of the clothes washing mechanism. 110

6. An apparatus of the class described comprising a frame, a driving mechanism supported therein, a reciprocatory clothes washing mechanism supported from the 120 frame, means to balance the weight of the clothes washing mechanism, means connected with the driving mechanism to reciprocate the clothes washing mechanism vertically, and a spiral gear in mesh with the 125 teeth of a spur gear for oscillating the clothes washing mechanism from one position to another position upon each upward stroke of the clothes washing mechanism.

7. In a washing machine the combination 130

with a driving mechanism of a reciprocatory and oscillatory washing member, a driving mechanism including a spur gear for reciprocating the washing member, said 5 spur gear also having spiral gear teeth superimposed thereon for oscillating the washing member.

8. An apparatus of the class described comprising a driving mechanism, a reciprocatory and oscillatory washing member, the driving mechanism including a plurality of spur gears for reciprocating said washing members, an arm slideable with respect to the washing member, a link connected therewith, and a spiral gear for reciprocating said link, said spiral gear being driven by one of the previously mentioned spur gears.

9. An apparatus of the class described comprising the combination with a wash tray 20 of a frame adapted to be secured to a fixed support above the wash tray, a vertically extending shaft passing through said frame, vacuum cups secured to the lower end of

the shaft, a spring in the frame, a cable connected with said spring, a pulley over 25 which said cable passes, said cable being connected to the vacuum cup shaft to support a portion of its weight, and means to reciprocate and oscillate the vacuum cups.

10. An apparatus of the class described comprising the combination with a wash tray 30 of a frame adapted to be secured to a fixed support above the wash tray, a vertically extending shaft passing through said frame, a guide arm loosely mounted 35 on said shaft, a guide shaft connected with said guide arm, a cable connected to said guide arm and to a spring to support the weight of the reciprocating parts, a pulley over which said cable passes, vacuum cups 40 secured to the lower end of the reciprocating shaft, and means to reciprocate and oscillate said shaft.

In testimony whereof I have hereunto set my hand this 13th day of Dec. A. D. 1920. 45

ALFRED E. ROBERTS.
